UNITED STATES PATENT OFFICE

JAMES EDW. GUNTER, OF BALTIMORE, MARYLAND

CONTAINER

Application filed April 12, 1926. Serial No. 101,310.

My invention relates to new and useful improvements in closures for containers and more particularly to one in which the cap retaining means may be readily removed without destroying the further usefulness of the cap or container.

An object of the invention is to provide a sealed container which may be economically manufactured; and which can be readily and 10 easily opened without the use of any tool, and a cap which after the container is opened may be satisfactorily used for closing the container while the contents are being used.

Another object of my invention is to provide 15 such a container with a double friction seal closure.

Another object of my invention is to make such a container in which the retaining ring acts as a prying means to release one of the 20 friction seals.

Another object of my invention is to make such a container in which the retaining ring has upon the container body means to hold it in its position.

25 Another object of my invention is to make such a container in which the means used for bending the cap over the retaining ring may be continuous peripherally, and in which the container itself requires no prior configurations to be made upon its surface for receiving the projecting handle of the retaining ring.

Further objects and advantages will be apparent from the following description and the 35 accompanying drawings:

Figure 1 is a cross sectional view on line 1—1 of Figure 2.

Figure 2 is a partial front view of the container as assembled with its cap and retaining ring.

Figure 3 is a partial cross sectional view on line 3—3 of Figure 4.

Figure 4 is a partial front view of another modification of the retaining ring and of the 45 means for holding it in place.

Similar numerals refer to similar parts throughout the several views.

The container body 1 has its walls substantially vertical, with a ridge 2 adjacent its 50 mouth or opening. Slightly below the ridge

2 is a second ridge 3 running parallel to the first ridge around the body of the container. Ridge 3 might take the form of projections 4 as shown in Figures 3 and 4.

Surrounding the container and between ridges 2 and 3 retaining ring 5 is placed and it has a handle 6 projecting from its path downwardly from under the container closure lip.

The projecting portion of the handle 6 is curved inwardly as shown at 7.

The cap 8 has double friction seals 9 and 10 with the upper edge of the container mouth. The inner lower shoulder of the cap is of substantially the same shape as the inner portion of the handle 7. The closure has a portion 11 which extends out over the retaining ring 5.

In assembling this modification the ring is first placed in its groove, and the cap placed in the container and seaming rolls or other means are used to bend the cap in against the 70 container and retaining ring and to press the lowermost edge 12 of the cap under the retaining ring. Lip 12 slightly overlaps the projecting ridge 3 as shown in Figure 1.

When the tool used to bend the lip 12 inwardly comes in contact with the handle 6 of the retaining ring it forces the portion 7 of the handle inwardly and distorts the container wall as shown in Figure 1 bending the projection 3 at that point in a curve reverse 75 from that in which it had previously been.

The portion of the container body back of the portion 7 of the handle is then in contact with the inner portion of the container cap. This construction enables uniform tools to 80 be used and does not require a previous indenting of the container or a previous thinning of the projecting portion of the handle, nor does it require a weakening of the outer lip 12 of the cap by making it discontinuous 85 in its lateral ring surrounding course. The upper part of the container cap may present an inverted V shape 14 to the top of the container mouth or opening, as shown in Figures 1 and 2. Upon replacing the cap after opening the container, the inner inwardly sloping cap wall makes a tight seal with the container mouth.

In the modification shown in Figures 3 and 4 the cap 13 has a longer inner friction seal 90

95

100

which extends below the retaining ring. In this modification the projections below the ring are spaced peripherally around the container body, and they are pointed as indicated in Figure 4, so that upon putting the ring upon the container should the projecting handle initially rest upon one projection its pointed surface will tend to cause the ring to creep around the body of the container until the handle is between two projections. In this modification also the handle has a thinned portion 5 at the point of its juncture with the ring which permits the bending tool to pass freely longitudinally around the retaining ring. This modification also does not require an indenting of the container by the retaining ring handle.

To remove the cap in either modification the handle is pulled outwardly thus bending up the lip 12 of the cap and breaking the outer friction seal 10. When the lip extends over the projection 3 as shown in Figures 1 and 2 the outward leverage on the handle is greater in its bending moment upon the lip 25 and the ring pulls out more readily. After initially pulling the handle outwardly the ring is pulled outwardly and around the container thus removing it and breaking the outer seal and the cap may be then readily 30 removed.

The retaining ring may be made of any material or it may have any cross section desired, its only requirement being that it hold its form under the stresses to which it is subjected, and that it have sufficient tensile 35 strength to be pulled out.

The only requirement of the container is that it be sufficiently tough and flexible in its walls to permit the projecting portion 7 of 40 the handle to be pressed into its side wall.

As many changes might be made in the above arrangements and as many variations might be made without departing from the scope of the invention, it is intended that all 45 the features herein described or shown in the accompanying drawings, shall be interpreted as illustrative, and that the invention be limited only by the following claims.

I claim:

1. The method of assembling a container having a flexible wall adjacent its mouth or opening with a cap and a retaining ring having a projecting handle, which consists in placing the retaining ring around the outer 55 wall of the mouth or opening of the container with the handle projecting away from said mouth or opening, placing the cap on the container, and applying inwardly directed pressures to the periphery of the cap to form a 60 bead thereon which longitudinally surrounds and partially encloses said retaining ring and presses the same firmly against said container, and depressing said flexible wall of the container with said handle at the place 65 where it projects from said bead.

2. The method of assembling a container having a flexible wall with a cap and a retaining ring having a projecting handle, which consists in placing the retaining ring around the mouth or opening of the container, with the handle projecting away from said mouth or opening, placing the cap on the container, bending a portion of the cap down and inwardly below and against said retaining ring, and depressing said flexible wall of the container with said handle at the place where it projects from said outer depending cap wall.

3. In combination, a container having a flexible wall adjacent its mouth or opening, 80 a cap closing the mouth or opening of the container and having an outer depending wall forming with the wall of the container a space, a retaining ring in said space having a handle projecting from said space, the 85 lower edge of said outer depending wall extending inwardly below said ring, and said flexible wall of the container being depressed by said handle at the place where it projects from said space.

4. In combination, a container having a flexible wall adjacent its mouth or opening, a cap on the container, an annular retaining ring having a projecting handle, said ring surrounding the mouth or opening of the container, with the handle projecting away from said mouth or opening, the edge of the cap forming a depending wall enclosing and surrounding said ring laterally to the extent that the inner diameter of the extreme lip of the cap bearing on the ring is less than the outer diameter of the ring, said flexible wall of the container being depressed by said handle at the place where it projects from under said depending wall.

5. A container seam comprising a flexible container wall, a retaining ring having a projecting handle and a removable and replaceable cap; characterized by the cap having an outer down-turned wall partially surrounding the retaining ring laterally and firmly holding it against the outer wall of the container, the handle projecting from under said down-turned wall, the flexible container wall being depressed by said handle at the place where it projects from under said down-turned wall.

6. A container seam comprising a flexible container wall, a retaining ring having a projecting handle and a removable and replaceable cap; characterized by the cap having an outwardly facing substantially vertical wall parallel to and engaging an inner wall of the container, the cap also having an outer down-turned wall partially surrounding the retaining ring laterally and firmly holding it against the outer wall of the container, the handle projecting from under said down-turned wall, the flexible container wall being depressed by said handle at the place where 130

- it projects from under said down-turned wall.
7. In combination, a container having a flexible wall adjacent its mouth or opening, a cap having an inner outwardly facing wall parallel to and engaging an inner wall of the container at its mouth or opening, the cap also having an outer depending wall forming with the outer wall of the container a space, a retaining ring around the container in said space having a handle projecting from said space, the lower edge of said outer depending wall extending inwardly below an outer periphery of said ring, and said flexible wall of the container being depressed by said handle at the place where it projects from said space. 70
- 10 8. In combination, a container, a cap having outer inwardly facing wall parallel to and engaging the outer wall of the container at its mouth or opening, the cap also having an outer depending wall forming with the outer wall of the container a space, a retaining ring around the container in said space having a handle projecting from said space, the lower edge of said outer depending wall extending inwardly below and against an outer periphery of said retaining ring. 80
- 15 9. A container seam for the end of a container comprising a container wall, a retaining ring surrounding the container wall near said end, a discontinuous ridge around and projecting outwardly from said wall immediately below said ring, a cap having a down-turned wall partially surrounding said ring laterally and underlapping said ridge, said ring having a projecting handle. 85
- 20 10. In combination, a container, a cap having an outer inwardly facing wall an upper portion being parallel to and engaging the outer wall of the container at its mouth or opening and a lower portion forming with a lower portion of the outer wall of the container a space, a retaining ring around the container in said space having a handle projecting from said space, the retaining ring being engaged and held in place by said lower portion of the cap wall. 90
- 25 11. In combination, a container, a cap having an outer inwardly facing wall an upper portion being parallel to and engaging the outer wall of the container at its mouth or opening, and a lower portion forming with a lower portion of the outer wall of the container a space, a retaining ring around the container in said space having a handle projecting from said space, means on said outer container wall, above said space, to hold said retaining ring downward on said container wall, the retaining ring being engaged and held in place upon the container by said lower portion of the cap wall. 100
- 30 12. In combination, a container, a cap having an outer inwardly facing wall an upper portion being parallel to and engaging the outer wall of the container at its mouth or opening, and a lower portion forming with a lower portion of the outer wall of the container a space, a retaining ring around the container in said space having a handle projecting from said space, means on said outer container wall to hold said retaining ring upward on said container wall, part of said lower portion of said second named wall being bent inwardly below and against said ring. 105
- 35 13. In combination, a container, a cap having inner outwardly facing and outer inwardly facing walls, said first named wall and an upper portion of said second named wall being parallel to and engaging the wall of the container at its mouth or opening, a lower portion of said second named wall forming with a lower portion of the outer wall of the container a space, a retaining ring around the container in said space having a handle projecting from said space, part of said lower portion of said second named wall being bent inwardly below and against said ring. 110
- 40 14. In combination, a container, a cap having inner outwardly facing and outer inwardly facing walls, said first named wall and an upper portion of said second named wall being parallel to and engaging the wall of the container at its mouth or opening, a lower portion of said second named wall forming with a lower portion of the outer wall of the container a space, a retaining ring around the container in said space having a handle projecting from said space, means on said outer container wall to hold said retaining ring upward on said container wall, part of said lower portion of said second named wall being bent inwardly below and against said ring. 115
- 45 15. In combination, a container, a cap having inner outwardly facing and outer inwardly facing walls, said first named wall and an upper portion of said second named wall being parallel to and engaging the wall of the container at its mouth or opening, a lower portion of said second named wall forming with a lower portion of the outer wall of the container a space, a retaining ring around the container in said space having a handle projecting from said space, means on said outer container wall to hold said retaining ring downward on said container wall, part of said lower portion of said second named wall being bent inwardly below and against said ring. 120
- 50 16. The combination with a container, of a cap having an inner outwardly facing wall, a lower portion being parallel to and engaging an inner wall of the container at its mouth, and an upper portion above the container wall flaring outwardly at a greater angle to the vertical than said inner wall of the container at its mouth, the cap also hav- 125
